UNITED STATES PATENT OFFICE

122,396

DESIGN FOR A TOY OR SIMILAR ARTICLE

Anne Farrell Herlihy, New York, N. Y.

Application June 14, 1940, Serial No. 92,999

Term of patent 3½ years

To all whom it may concern:

Be it known that I, Anne Farrell Herlihy, a citizen of the United States, residing at New York, in the county of New York and State of New York, have invented a new, original, and ornamental Design for a Toy or Similar Article, of which the following is a specification, reference being had to the accompanying drawing, forming part thereof.

The figure is a perspective view of a toy, showing my new design.

I claim:

The ornamental design for a toy or similar article, as shown.

ANNE FARRELL HERLIHY.
